E. M. RICHARDS

PINCUSHION

Filed Feb. 23, 1922

Inventor
Edith M. Richards,
By Louis M. Schmidt
Attorney

UNITED STATES PATENT OFFICE.

EDITH M. RICHARDS, OF HARTFORD, CONNECTICUT.

PIN CUSHION.

Application filed February 23, 1922. Serial No. 538,660.

To all whom it may concern:

Be it known that I, EDITH M. RICHARDS, a citizen of the United States, residing at Hartford, in the county of Hartford and State of Connecticut, have invented certain new and useful Improvements in Pin-cushions, of which the following is a specification.

My invention relates to improvements in pin-cushions of the form comprising the combination of a doll-figure and a pin-cushion, and the object of my improvement is to produce a combination of a full-length figure and a pin-cushion structure that encircles the body of said figure in lieu of a dress structure and that, furthermore, is provided at the head with a head band of ribbon that is extended to provide means for suspension, and, also, as a detail, there may be provided a decoration at the back in the form of a bow or fanciful arrangement of ribbon that is supported from the pin-cushion structure.

In the accompanying drawing:—

Figure 1 is a side elevation of my improved pin-cushion doll in the suspended position.

Figure 2 is a front elevation of the same in the upright position, the suspension ribbon being in part broken away.

Figure 3 is a rear elevation of the same.

My improved pin-cushion doll comprises a doll-figure 10 in the form of an erect, full-length image of fanciful form of an infant or small child that is provided around the body 11 in lieu of other clothing or a dress with a pin-cushion structure 12 that extends generally from below the arms 13 downwardly to adjacent and just above the knees, the major and lower parts of the legs 14 being exposed and uncovered and the feet 15 may or may not be covered with slippers 24.

The pin-cushion structure 12 is puffed outwardly and rounded and stuffed in any proper manner so as to be serviceable as a pin-cushion.

At the back and at the upper border of the pin-cushion structure 12 is mounted a decoration in the form of a bow 16 of ribbon.

The head 17 is encircled generally transversely by a headband 18 of ribbon that is smooth at the front 19 and is knotted at the

back, as shown at 20, and the ends 21 of the ribbon are preferably appreciably extended in length and terminate in the form of a bow 22. Thus the ribbon ends 21 serve to enclose a loop 23 that is relatively large and is adapted to be slipped over a support, which may be a projection on a dresser or bureau, or a nail or hook.

Thus the device will be convenient for use and at the same time will serve as an attraction as a novelty.

Shoulder straps 25 of ribbon may be provided extending over the shoulders of the figure 10 and connected by the ends to the pin-cushion structure 12.

As described, the pin-cushion structure is of globular form with an opening along the axis and has a supporting structure of unique form projected through said opening. Such form comprises a doll figure, having arms, shoulders, and head projected above the upper end of the pin-cushion structure 75 and projected below the lower end thereof are the knees, the lower parts of the limbs, and the feet.

In one position, the feet are adapted to serve as the base or support proper. In another position, the head band serves as the connection with the loop of ribbon that operates as a suspension device, the effective connection with the head being positioned at the rear side.

In the suspended position the supporting figure is tilted at an angle. The axis of the figure and of the pin-cushion structure being substantially coincident, the latter is also tilted, the equatorial plane being at an appreciable angle to the horizontal.

As mentioned, the pin-cushion structure serves in lieu of clothing for the doll-structure and such clothing or covering is confined substantially to the body or torso of the figure.

The tilting position follows because the head is of appreciable thickness, the supporting connection is at the rear side thereof, and the center of gravity is inside the pin-cushion structure.

Fig. 1 shows the structure in the suspended position, and with the tilting effect slightly exaggerated.

I claim as my invention:—

In combination in a pin-cushion structure,

a pin-cushion body of globular form, a core figure in the form of a doll extended along the axis of said body and having the head and the legs projected beyond the upper and lower surfaces, respectively, of the cushion body, and a ribbon serving as a suspension support for said structure, and said ribbon

having the body portion positioned as a head-band around said head and having the end portions extended from said body portion at the rear of said head and united in loop form to provide the suspension support proper.

Miss EDITH M. RICHARDS.
